Primary Examiner — Cynthia M Chin*(74) Attorney, Agent, or Firm* — QuickPatents; Kevin Prince(57) **CLAIM**

I claim the ornamental design for a pneumatic gun bolt, as shown and described.

DESCRIPTION

FIG. 1 is a partially exploded top perspective view of a pneumatic gun bolt, showing my new design;

FIG. 2 is an exploded top perspective view thereof;

FIG. 3 is a bottom perspective view thereof;

FIG. 4 is an exploded bottom perspective view thereof;

FIG. 5 is an exploded front elevational view thereof, the rear elevational view being a mirror image thereof;

FIG. 6 is an exploded top plan view thereof; and,

FIG. 7 is an exploded bottom plan view thereof.
